BITT-CHOCK

Charles G. Halpine, United States Navy

Application April 22, 1937, Serial No. 138,410

5 Claims. (Cl. 114—101)

(Granted under the act of March 3, 1883, as
amended April 30, 1928; 370 O. G. 757)

This invention relates to chocks and has a particular relation to chocks employed to hold a towing or mooring line in proper position on the object being towed or moored.

5 The principal object of the present invention is the provision of a chock of the character described that is particularly adapted for use on seaplane floats where the lead of the tow line is appreciably upward and where there is a tendency for the tow line to become dislodged from the chock, due to the yaw or pitch of the float.

Another object of the invention is the provision of a chock of the type described which will permit the tow line to be quickly and easily positioned 15 therein but which will effectually prevent it from becoming displaced therefrom, irrespective of the angle of the tow line.

Another object of the invention is the provision of a chock of simple construction which may be 20 cast as a unitary structure.

With these and other objects in view, as well as other advantages that may be incident to the use of the improvements, the invention consists in the parts and combinations thereof hereinafter 25 set forth and claimed, and with the understanding that the several necessary elements constituting the same may be varied in proportion and arrangement without departing from the nature and scope of the invention, as defined in the appended claims.

In order to make the invention more clearly understood, there are shown in the accompanying drawing, means for carrying the invention into practical use, without limiting the improvements in their useful application to the particular construction, which, for the purpose of explanation, have been made the subject of illustration.

In the accompanying drawing:
40 Fig. 1 is a perspective view of the improved chock;

Fig. 2 is a plan view, on a smaller scale, of the chock and associated securing bitts, showing the tow line in different transverse positions; and
45 Fig. 3 is a similar view illustrating the manner in which the invention may be employed as a combined chock and bitt.

Referring to the drawing, the improved chock is shown as comprising a base plate 10 adapted 50 to be secured to the upper surface of a seaplane float or to the deck of a vessel by fastening means 11 passing through openings 12 formed in the base plate. Two vertically extending posts 13 and 14 are carried by the base plate 10, preferably 55 being cast integrally therewith, and are arranged

approximately in a fore and aft spaced relation and slightly, but not necessarily, offset laterally with respect to one another. These posts 13 and 14 are formed with laterally extending horns or fingers 15 and 16 for preventing accidental displacement of the line in a vertical direction. The forward post 13 is also formed with an arm or extension 17 which projects laterally and then rearwardly toward the post 14 and terminates with a downwardly extending hook 18.

5 In practice, a tow line 19 is initially positioned within the chock by passing it beneath arm 17 and hook 18 and then over the top of the post 14. The running end of the line 19 may be made fast on a pair of bitts 20 located aft of the chock, or in 15 any other suitable manner.

It will be noted from an inspection of Figs. 2 and 3, that with the described construction, the tow line may assume a plurality of different lateral positions without becoming disengaged 20 from the chock, the post 13 and hook 18 limiting the swinging movement of the tow line in opposite directions. In view of the fact that the tow line nearly always extends upwardly at an angle to the surface of the water and is under tension, 25 the hook 18 will prevent the line from escaping from beneath the extension 17.

In Fig. 3 there is illustrated another method of securing the tow line to the chock. In this case, the tow line passes aft beneath the extension 17, 30 around the post 14, and thence forwardly around the post 13 and again beneath the extension in the conventional "figure 8" manner. This method of securing the line dispenses with the bitts 20, the posts 13 and 14 themselves functioning as bitts.

35 It will be understood that the terms "fore" and "aft" have been employed for convenience of explanation, as the chock may be mounted on the stern where its position will be reversed. Also, 40 it is not necessary to provide the posts 13 and 14 on a common base, as these elements may be separately mounted.

45 Other modifications and changes in the proportions and arrangement of the parts of this device or other adaptations of its use may be made by those skilled in the art without departing from the nature and scope of the invention, as defined in the appended claims.

The invention described herein may be manufactured and used by or for the Government of the United States of America for governmental purposes without the payment of any royalties thereon or therefor.

I claim:

55

1. A chock comprising a post; and a second post arranged in spaced relation to said first mentioned post, said first mentioned post being provided with an arm projecting laterally to a point offset with respect to said second post and thence longitudinally to a point in substantially lateral alignment with and in spaced relation to said second post for preventing a line disposed between said posts from becoming displaced therefrom by strains exerted along said line.
2. A chock comprising a post; and a second post arranged in spaced relation to said first mentioned post, said first mentioned post being provided with an arm projecting laterally to a point offset with respect to said second post and thence longitudinally to a point in substantially lateral alignment with and in spaced relation to said second post and terminating in a downwardly extending hook for preventing a line disposed between said posts from becoming displaced therefrom by strains exerted along said line.
3. A chock comprising a post; and a second post arranged in spaced relation to said first mentioned post, said first mentioned post being provided with arms extending in opposite directions, one of said arms projecting laterally to a point offset with respect to said second post and thence longitudinally to a point in substantially lateral alignment with and in spaced relation to said second post and terminating in a downwardly extending hook for preventing a line disposed be-

tween said posts from becoming displaced therefrom by strains exerted along said line.

4. A chock comprising a post; and a second post arranged in spaced relation to said first mentioned post, said first mentioned post being provided with an arm projecting laterally to a point offset with respect to said second post and thence longitudinally to a point in substantially lateral alignment with and in spaced relation to said second post, the axis of said second post lying without a vertical plane containing the vertical axis of said first mentioned post and disposed normal to the axis of direction of the laterally projecting portion of said arm, said arm preventing a line disposed between said posts from becoming displaced therefrom by strains exerted along said line.

5. A chock comprising a post; and a second post arranged in spaced relation to said first mentioned post, both of said posts being provided with arms extending in opposite directions, one of the arms of the first mentioned post projecting laterally to a point offset with respect to said second post and thence longitudinally to a point in substantially lateral alignment with and in spaced relation to the end of the corresponding arm of said second post, said arms preventing a line disposed between said posts from becoming displaced therefrom by strains exerted along said line.

CHARLES G. HALPINE.
